(57) **CLAIM**

I claim the ornamental design for the shot gun lighter, substantially as shown and described.

DESCRIPTION

FIG. 1 is a front elevation view of the shot gun lighter with its ignition device in a disposed position of use;

FIG. 2 is a front elevation view of the shot gun lighter with its ignition device in a position of use;

FIG. 3 is a right side elevation view of FIG. 1;

FIG. 4 is a left side elevation view of FIG. 1;

FIG. 5 is a top plan view of FIG. 1; and,

FIG. 6 is a bottom plan view of FIG. 1.

The broken line environmental showing is for illustrative purposes only and forms no part of the claimed design.
